SLIDER FOR SLIDE FASTENERS

Alfred E. Carlile, Meadville, Pa., assignor to
Talon, Inc., a corporation of PennsylvaniaApplication December 12, 1935, Serial No. 54,096
Renewed July 13, 1938

3 Claims. (Cl. 24—205)

My invention relates to slide fasteners and more particularly to that element of slide fasteners which is called the slider.

One of the objects of my invention is to provide an improved slider which has a minimum over-all thickness and at the same time, has means for conveniently operating the same. In the use of slide fasteners in the plackets of women's dresses and in men's trousers it is found that the usual type of slider with an upwardly projecting loop or lug causes difficulties in pressing the garments. The lug of the slider will press into the garment and make the location of the slider apparent even though it is concealed behind a flap.

15 One of the objects of my invention is to provide an improved slider which has a minimum over-all thickness and at the same time, has means for conveniently operating the same.

A more specific object of the invention is to 20 provide a slider with a pull tab hinged to the slider in such a way that it may be swung up over the slider for easy operation, or swung to one side of the slider where it does not increase the over-all thickness of the slider and at the same 25 time, if desired, the slider may be operated from the side.

In the accompanying drawing I have shown for 30 purposes of illustration three embodiments which my invention may assume in practice. In this drawing:

Fig. 1 is a plan view of a portion of a slide fastener having my improved slider mounted thereon;

Fig. 2 is a perspective view of a slider showing 35 a slightly modified form of pull tab;

Fig. 3 is a cross-section on line 3—3 of Fig. 1; and

Fig. 4 is a perspective view showing the modified construction.

40 My invention is applicable to any known type of slide fastener and the one illustrated is well known and widely used. It will therefore not be described in detail. It comprises generally a pair of flexible tapes 5, 6 having corded edges 7.

Attached to the corded edges in uniformly spaced 45 relation are cooperating rows of fastener elements 8. The slider is mounted to slide along these fastener elements and has upper and lower flanged wings 9, 10, respectively, so as to guide

50 the elements on both sides of the tapes. The upper wing of the slider is made somewhat thicker than the lower wing but its upper surface is flat and smooth. A pair of bearing recesses 11 are formed in opposite ends of the upper wing

55 and a pull tab 12 has arms 13, 14 whose ends are

turned in to provide pivots or journals fitting in the recesses 11. Preferably the pull tab has a knurled flat portion 15 of substantial area so that it can be easily gripped by the user. The pull tab is so designed that there will be the 5 opening 16 between the arms 13, 14 which opening is of approximately the size and shape of one side of the slider to permit the pull tab to swing around to the side of the slider. While the garment is in use the pull tab will ordinarily lie 10 flat in the plane of the slider as illustrated in the full line positions of Figs. 1 and 2. In this position it will not penetrate into the material of the garment and interfere with pressing operations. If desired this tab may be gripped from the side 15 to operate the slider but preferably it will be lifted to the dotted line position indicated in Fig. 2. If desired also the pull tab may be swung to the dotted line position indicated in Fig. 1 when not in use.

20 In Fig. 2 the knurled portion is extended around one end of the slider as shown at 17.

In the modified form shown in Fig. 4 the upper wing 18 of the slider is made of the usual thickness and the bearing recesses 19, 20 are provided 25 by suitably deforming the metal. The upward projections required for this purpose will not seriously interfere with the appearance of the article to which the fastener is applied and will not interfere with the pressing operation.

30 While I have shown and described in this application three embodiments which my invention may assume in practice, it will be understood that these embodiments are merely for the purposes of illustration and description and that various other forms may be devised within the scope 35 of my invention as defined in the appended claims.

What I claim as my invention is:

1. A slider for slide fasteners of the class described including upper and lower wings, the top 40 wing having a substantially flat outer surface, a pull member hinged to the top wing to swing about an axis extending longitudinally of the slider and fastener, the bearing means which connects the pull to the slider being formed in the 45 opposite ends of the wing, the pivot axis being in the plane of the wing and said pull being swingable to a position at one side of the slider in which position no part of the same projects above the flat surface of the top wing. 50

2. A slider for slide fasteners as defined in the preceding claim wherein said pull member has a gripping portion of substantial area which extends laterally of the slider when the same is 55 swung into the plane of the top wing and which

extends upwardly in line with the center line of the slider when the pull is swung upwardly.

3. A slider for slide fasteners of the class described including upper and lower wings in substantially parallel relation with a channel between them for receiving the fastener elements of a slide fastener, a pull member pivotally connected to the top wing to swing about an axis

extending longitudinally of the slider and fastener, the pull member comprising a central pull portion, arms extending from the central portion, the ends of the arms being turned in toward each other to provide pivots or journals, and bearing recesses formed in opposite ends of the upper wing for receiving said pivots or journals. 5

ALFRED E. CARLILE.
